UNITED STATES PATENT OFFICE.

EDWARD G. NIKLAUS, OF MADISON, INDIANA.

DESIGN FOR A BUTTON.

SPECIFICATION forming part of Design No. 25,090, dated January 28, 1896.

Application filed August 8, 1895. Serial No. 558,684. Term of patent 3¹ years.

To all whom it may concern:

Be it known that I, EDWARD G. NIKLAUS, of Madison, county of Jefferson, State of Indiana, have invented and produced a new and original Design for Buttons, of which the following is a specification, reference being had to the accompanying drawings.

In the accompanying drawings, Figure I is a top plan view of my button on a magnified scale. Fig. II is a central vertical section thereof.

The essential feature of my device consists in the representation upon the face of a button of a hemisphere and a bug in the midst of it.

Referring to the figures on the drawings, 1 indicates the disk-shaped button provided upon its top with a circular peripheral bead 4 and with a milled edge 5.

6 indicates the representation of a hemisphere of a smaller diameter than the diameter of the circular bead 4 and concentric with it, defining between the hemisphere and the bead a zone 7 ornamented with rays 8. The hemisphere is provided with raised lines 9 to represent degrees of longitude and latitude and coast-lines 10 to represent the continents.

11 indicates the representation of a bug in the midst of the hemisphere and in relief.

The button of the configuration and ornamentation specified is designed to be fastened in practice by any suitable or ordinary means—as, for example, the shank 2 and base 3; but the fastening mechanism forms no part of my design.

What I claim is—

The design for a button herein shown and described.

In testimony of all which I have hereunto subscribed my name.

EDWARD G. NIKLAUS.
